E. WILLIAMS.

ROCKING CHAIR.

No. 15,252.

Patented Aug. 12, 1884.

UNITED STATES PATENT OFFICE.

EDWARD WILLIAMS, OF CHELSEA, MASSACHUSETTS.

DESIGN FOR A ROCKING-CHAIR.

SPECIFICATION forming part of Design No. 15,252, dated August 12, 1884.

Application filed June 13, 1884. Term of patent 14 years.

To all whom it may concern:

Be it known that I, EDWARD WILLIAMS, of Chelsea, in the county of Suffolk and State of Massachusetts, have invented a new and original Design for Chairs, of which the following is a specification.

This design relates to reed chairs, and has for its object to impart a pleasing effect to the marginal portion of the back and of the arms.

10 The nature of the design is fully shown in the accompanying photographic illustration.

The design consists in the openings *o o* in the marginal frame *f*, separated by straight strands or strips *s s*, which connect the outer 15 and inner portions, 2 3, of said frame.

The openings and the intermediate straight strips, *s*, making the openings angular, constitute the novel features of the design, and distinguish the chair from those in which the 20 marginal frame of the back is composed of an

outer and inner part connected by strips which have the form of loops or rings, as in many rattan chairs now in use, and therefore constitute openings which are not angular, but are bounded by the said loops or rings. 25

It will be seen, by reference to the illustration that a pleasing effect is produced by the described design.

I claim—

The design for a chair, consisting of the angular openings in the marginal back-frame, as set forth.

In testimony whereof I have signed my name to this specification, in the presence of two subscribing witnesses, this 10th day of May, 35 1884.

EDWARD WILLIAMS.
